TELEPHONE SYSTEM.

1,071,207.

Specification of Letters Patent. Patented Aug. 26, 1913.

Application filed September 17, 1908, Serial No. 453,541. Renewed August 14, 1911. Serial No. 644,043.

To all whom it may concern:

Be it known that we, ELMER R. CORWIN and CHARLES A. BALS, citizens of the United States of America, residing at Chicago, in the county of Cook and State of Illinois, have invented a new and useful Telephone System, of which the following is a specification, reference being had to the accompanying drawing, illustrating same.

10 Our invention relates to telephone systems having automatic calling mechanism and automatic operator's-control mechanism.

The principal objects of our invention are, to provide improved means for automatically calling subscribers when connection is made with their lines; to provide improved means for automatically controlling such calling apparatus; to provide improved means for controlling the operator's connection with the various cord circuits of the system; and to provide other improved circuit arrangements hereinafter described.

The accompanying drawing is a diagrammatic illustration of a pair of telephone lines extending from substations to a central exchange, and a connecting circuit for the lines having the necessary apparatus associated therewith for operating the system in accordance with this invention.

30 The line of subscriber A extends in two limbs 1 and 2 to suitable connection terminals 3 and 4, respectively, of a spring jack C at the central exchange. Terminals 3 and 4 normally engage contacts 5 and 6, respectively, but are adapted to disengage these contacts when a plug is inserted into the jack. Contact 5 extends through a line lamp 7 to the live pole 8 of battery D, the opposite pole 9 of battery D being grounded. Contact 6 is connected direct to ground, as is also the thimble 10 of the jack C. At the substation A, limb 2 of the line is normally connected through ringer 11 and a condenser 12 to ground, this connection to ground being broken when the receiver is removed from the switch-hock 13 in the ordinary manner. Substation A also contains the ordinary talking apparatus. The line of subscriber B is similar to line A and like characters have been used to represent like parts in connection with the two lines.

In the plug-cord connecting circuit the answering plug E and the calling plug F have their tip contacts 14 and 15 connected together, respectively,

through respective condensers 16 and 17, these strands through the plug-cord circuit constituting the metallic talking circuit through the connecting circuit when the connecting plugs E and F are connected with lines. The 60 plugs E and F have their sleeve contacts 18 and 19 connected through respective windings 19 and 20 of an operator's differential relay H to pole 8 of battery D. The windings of this relay are so arranged that when either 65 one of the connecting plugs E or F is connected with a line the relay will be energized and will thereby connect the operator's telephone set with the corresponding connecting circuit, the operator's telephone set being 70 normally disconnected from the connecting circuit at contacts 21 and 22 and 23 and 24 which are controlled by the relay H, and the battery circuit of the operator's transmitter 25 being normally open at contact 26 which 75 is also controlled by relay H. The windings of relay H are also arranged so that when both of the connecting plugs E and F are connected with lines the relay H is deenergized, 80 under these conditions the windings 19 and 20 of relay H acting differentially. Therefore it will readily be seen that it is impossible for the operator to "listen in" on a connection established between two lines, and that the operator's set is controlled by a 85 single relay for each pair of cords before her. J is an impedance coil through which talking battery from battery D is supplied to the operator's transmitter 25.

The answering supervisory lamp 28 is 90 controlled by contact 29 which is controlled by relay K. This relay K also serves as an impedance to both limbs of the metallic talking circuit. When the calling plug F is connected with a line, relay L becomes 95 energized and thereby closes normally open contacts 31 and 32 and 33 and 34. These contacts control the circuits of the ringing generator G and the interrupter M, respectively, as will be hereinafter described. Contact 31 and 32 is in a limb of the talking circuit. The interrupter M when operated periodically closes and opens a contact 35 and 36 which is in the circuit of winding 43 of relay N, so that the interrupter M will control the operation of 100 relay N as will be hereinafter described. The calling supervisory lamp 37 is controlled by a contact 38 and 39 which is controlled by relay N. Relay N also controls a normally closed contact 40 and 41 in the cir- 110

cuit of ringing generator G, and a normally open contact 41 42 in a limb of the talking circuit. Winding 44 of relay N is connected from a limb of the plug-cord talking circuit to pole 8 of battery D, and in addition to energizing the relay N as will be hereinafter described, it serves as an impedance to this limb of the talking circuit. Winding 45 of relay P in addition to energizing relay P as will be hereinafter described, also serves as an impedance to one of the limbs of the talking circuit. Relay P controls a normally closed contact 46 47 in the circuit of ringing generator G, a normally closed contact 48 49 in the circuit of interrupter M, a normally closed contact 50 51 in the circuit of winding 43 of relay N, and a normally open contact 50 52 in circuit with winding 53 of relay P. The contact 50 52 is for the purpose of causing relay P to lock itself in operated position from the time the circuit of the line is closed while the calling plug F is connected therewith, until the plug F is disconnected from the line, for purposes hereinafter described. The contacts 14, 15 and 18 of each of the connecting plugs E and F register with contacts 3, 4 and 10 of a jack C when connection is made with a line.

The operation of the system is as follows: Assuming that subscriber A desires to call and converse with subscriber B, he first removes his telephone receiver from the switch-hook which closes the circuit of his metallic line through his substation and thereby closes a circuit of battery D through line lamp 7 belonging to line A, and through the metallic line A back to ground at the central station. Current from battery D flowing through this circuit lights the line lamp 7 which conveys to the operator a signal for connection. The operator then inserts the answering plug E into the jack C of line A and by so doing opens jack contacts 3 5 and 4 6 to prevent the line lamp 7 of line A from displaying a signal, and closes the following circuits: First. From pole 8 of battery D through winding 19 of relay H and plug-jack contact 18 10 of line A to ground. Current from battery D flowing through this circuit energizes relay H and thereby causes same to close contacts 21 22, 23 24 and 26 27, which bridges the operator's telephone set across the metallic plug-cord talking circuit and also supplies the operator's transmitter 25 with battery from pole 8 of battery D through impedance coil J, contact 27 26, and transmitter 25 to ground. Second. From pole 8 of battery D through winding 54 of relay K, through the metallic line A, and through winding 55 of relay K to ground. Current from battery D flowing through this circuit energizes relay K and thereby causes same to open contact 29 30 to prevent the supervisory lamp 28 from displaying a signal. Now the

operator converses with the party at substation A and finds out from him that the party at substation B is desired. The operator now inserts the calling plug F into the jack C of line B, which opens jack contacts 3 5 and 4 6 to prevent the line lamp 7 of line B from displaying a signal, and closes, or causes the closure of, a number of circuits as follows: First. From pole 8 of battery D through winding 20 of relay H, and plug-jack contact 18 10 of line B to ground. Current from battery D flowing through this circuit causes relay H to become deenergized, because windings 19 and 20 of relay H now act differentially, and thereby open contacts 21 22, 23 24 and 26 27, which disconnects the operator's set from the plug-cord talking circuit and opens the battery circuit through the operator's transmitter 25. Second. From pole 8 of battery D through calling supervisory lamp 37, contact 38 39 of relay N, and plug-jack contact 18 10 of line B to ground. Current from battery D flowing through this circuit causes supervisory lamp 37 to display a signal, which indicates to the operator that line B is not taken for use. Third. From pole 8 of battery D through the winding of relay L, and plug-jack contact 18 10 of line B to ground. Current from battery D flowing through this circuit energizes relay L and causes it to close contacts 31 32 and 33 34. Fourth. Contact 31 32 being closed closes a circuit of ringing generator G through contact 46 47 of relay P, contact 40 41 of relay N, contact 32 31 of relay L, plug-jack contact 15 4, limb 2 of line B, ringer 11, and condenser 12 to ground. Current from ringing generator G flowing through this circuit operates the ringer 11 at substation B and thereby signals the party at substation B to answer his telephone. Fifth. Contact 33 34 being closed closes a circuit from pole 8 of battery D through the armature of interrupter M, contact 48 49 of relay P, contact 34 33 of relay L, and plug-jack contact 18 10 of line B to ground. Current from battery D flowing through this circuit starts the operation of interrupter M and thereby causes it to periodically close and open contact 35 36, as will be readily understood. Sixth. When contact 35 36 is closed it closes a circuit from pole 8 of battery D through contact 35 36 of the interrupter M, winding 43 of relay N, contact 51 50 of relay P, and plug-jack contact 18 10 of line B to ground. Current from battery D flowing through this circuit energizes relay N and causes same to open contacts 38 39 and 40 41, and close contact 41 42. Contact 38 39 being open extinguishes the supervisory lamp 37. Contact 40 41 being open stops the flow of current from ringing generator G over line B. Contact 41 42 being closed closes a break 130

in a limb of the plug-cord talking circuit to complete the continuity of said talking circuit. In a few seconds the continuous operation of the interrupter M causes contact 35 36 to again become open, which de-energizes relay N and causes it to open contact 41 42 and close contacts 40 41 and 38 39. Contact 40 41 being now closed causes ringing current from ringing generator G to again flow over limb 2 of line B and again ring the ringer at substation B. Contact 38 39 being now closed again causes the supervisory lamp 37 to display a signal. As the operation of the interrupter M continues it causes ringing current to be sent periodically over limb 2 of line B to periodically ring the ringer 11 at substation B, and also causes the supervisory lamp 37 to give a signal periodically, simultaneously with the ringing of the ringer at substation B, in the manner described above. When the party at substation B answers his call he removes his receiver from the switch-hook in the usual manner, which closes the circuit between the limbs of his line and thereby closes a circuit from pole 8 of battery D through winding 44 of relay N, contact 42 41 of relay N, contact 32 31 of relay L, plug-jack contact 15 4 of line B, the metallic line B, plug-jack contact 3 14 of line B, and winding 45 of relay P to ground, provided interrupter M has contact 35 36 closed so as to energize relay N and thus cause the latter to have contact 41 42 closed; this condition being attained as soon as the interrupter M closes contact 35 36 after the party at substation B removes his receiver from the switch-hook, if the contact 35 36 is not already closed when the receiver is taken for use. Current flowing through this circuit gives additional energy to relay N and also energizes relay P and causes the latter to open contacts 46 47, 48 49 and 50 51, and close contact 50 52. Contact 46 47 being open prevents the flow of ringing current from ringing generator G over line B. Contact 48 49 being open stops the operation of interrupter M, provided the interrupter M is not operated by having its armature circuit closed by apparatus of other cord circuits. Contact 50 51 being open prevents current from flowing through winding 43 of relay N, even if interrupter M should be still in motion so as to periodically close contact 35 36. Contact 50 52 being closed closes a circuit from pole 8 of battery D through winding 53 of relay P, contact 52 50 of relay P, and plug-jack contact 18 10 of line B to ground. Current from battery D flowing through this circuit keeps relay P energized until the plug F is disconnected from the jack C, independent of whether a circuit of battery D is closed through winding 45 of relay P or not. Now the parties at substations A and B are connected for conversation with each other, the talking circuit being continuous through contacts 31 32 and 41 42 of relays L and N, respectively, all of the relays except relay H being now energized. When the conversation is completed and the party at substation A hangs his receiver upon the switch-hook he opens the circuit of his metallic line at his substation and thereby stops the flow of current through supervisory relay K, thus allowing relay K to release its armature and close contact 29 36. Contact 29 30 being closed closes a circuit from pole 8 of battery D through contact 30 29, answering supervisory lamp 28, and plug-jack contact 18 10 of line C to ground. Current from battery D flowing through this circuit lights the supervisory lamp 28, which indicates to the operator that the party at substation A has finished with the use of his line. When the party at substation B hangs his receiver upon the switch-hook he opens the circuit of his metallic line at his substation and thereby stops the flow of current through winding 45 of relay P and winding 44 of the calling supervisory relay N, thus allowing relay N to release its armatures and thereby open contact 41 42 and close contacts 40 41 and 38 39. Contact 38 39 being closed closes a circuit from pole 8 of battery D through calling supervisory lamp 37, contact 38 39 of relay N, and plug-jack contact 18 10 of line B to ground. Current from battery D flowing through this circuit lights the supervisory lamp 37, which indicates to the operator that the party at substation B has finished with the use of his line. The operator now withdraws the connecting plugs E and F from their respective spring jacks C C, thereby opening the circuits of lamps 28 and 37 and extinguishing their signals. This disconnection of the lines also opens the circuits through the winding of relay L and through the winding 53 of relay P, thereby permitting the armatures of these relays to release and take their normal positions. In making this disconnection the operator also opens the circuits through windings 19 and 20 of relay H, thereby stopping the flow of current through these windings 19 and 20. Now all of the circuits and apparatus are in their normal position and condition, ready for other connections to be made for conversation between the lines of the system.

We do not wish to limit this invention to all of the particular details, or to the particular pieces of apparatus, herein shown, as various modifications may be made therein without departing from the scope of the appended claims.

What we claim as our invention is:

1. The combination in a telephone system having lines, of a connecting circuit for the

- lines, a source of ringing current, a ringing relay associated with the connecting circuit for applying the source of ringing current to a line when connection is made therewith, a supervisory signal, a supervisory relay having switching mechanism controlling the circuits of the source of ringing current and the said supervisory signal, an interrupter controlling a circuit of the supervisory relay whereby the latter causes periodic ringing and a periodic operation of the said supervisory signal when connection is made with a called line, the said interrupter being under control of the ringing relay, a locking relay adapted to be operated when the line with which connection is made is taken for use, and switching mechanism under control of the locking relay whereby the latter controls the circuits of the source of ringing current, of the interrupter, of the supervisory relay, and its own circuit, when the line is taken for use while connection is made therewith, whereby said locking relay is locked in operated position until connection is disestablished with the line.
2. The combination with a telephone system having lines, of a connecting circuit for the lines, a source of ringing current, a ringing relay, a supervisory relay, and a locking relay, associated with the connecting circuit and each having switching mechanism controlling the circuit of the source of ringing current, and an interrupter controlling a circuit of the supervisory relay whereby periodic ringing is produced when connection is made with a called line, the said ringing relay applying ringing current to the called line when connection is made therewith, and the said locking relay preventing the ringing current from being applied to the line after the same is taken for use while connection is made therewith.
3. In a telephone system having lines, a connecting circuit for the lines, said connecting circuit having a talking strand therethrough, said talking strand having a section thereof disconnected therefrom, a source of calling current normally connected with said section of the talking strand, a relay for connecting said section with a line when connection is made therewith, a second relay controlling the connection of said section with said talking strand, and an interrupter controlling said second relay whereby the source of calling current is periodically disconnected from said section when connection is made with a called line, to give periodic signaling over the line.
4. The combination with a telephone system having lines, of a connecting circuit therefor, said connecting circuit having a talking strand therethrough, a source of calling current normally connected directly with a section of said talking strand, a relay for continuing the circuit of said calling source
- over a line when connection is made therewith, and interrupter means apart from the circuit of the said source of calling current for periodically controlling the connection of said calling source with said section of the talking strand, substantially as described.
5. The combination with a telephone system having lines, of a connecting circuit therefor, said connecting circuit having a talking strand therethrough, said talking strand having a break therein, a source of calling current normally connected directly with a section of said talking strand, means apart from the circuit of the said source of calling current for periodically controlling the connection of said source of calling current with said section of the talking strand, and means for permanently disconnecting said source of calling current from said talking strand and permanently establishing the continuity of said talking strand when the called line is taken for use while connection is made therewith.
6. In a telephone system having lines, a connecting circuit for the lines, said connecting circuit having a talking strand therethrough, a break in said talking strand, a source of wave form ringing current normally connected directly with a section of said talking strand by non-conductive connections, and means apart from the ringing circuit for disconnecting said source of calling current from said talking strand and establishing the continuity of said talking strand when the called line is taken for use while connection is made therewith.
7. The combination in a telephone system having lines, of a connecting circuit for the lines, said connecting circuit having a talking strand therethrough, said talking strand having a break therein, a source of calling current normally connected directly with a portion of said talking strand, means apart from the circuit of the said source of calling current for causing periodic signaling from said source of calling current over a called line when connection is made therewith, and means for disconnecting said source of calling current from said talking strand and establishing the continuity of said talking strand when the called line is taken for use while connection is made therewith.
8. The combination with a telephone system having lines, of a connecting circuit for the lines, said connecting circuit having a metallic talking circuit therethrough and a third strand, a source of ringing current normally connected with a portion of the said metallic talking circuit, a ringing relay for applying ringing current over a called line when connection is made therewith, said ringing relay being connected with said third strand and being operated when connection is made with a line, an interrupter, means whereby said ringing relay controls

- the circuit of said interrupter, a supervisory relay controlling the circuit of said source of ringing current and a portion of the said metallic talking circuit, a supervisory signal under control of said supervisory relay, means whereby the said interrupter controls a circuit of the said supervisory relay whereby the latter causes periodic ringing over a called line when connection is made therewith, and simultaneous periodic operation of said supervisory signal, a locking relay controlling a circuit of its own, the circuit of the said source of ringing current, the circuit of the said interrupter, and the said circuit of the supervisory relay, said supervisory relay and said locking relay having respective windings which serve as impedances for the respective limbs of said talking circuit and whereby the said relays are energized when the line with which connection is made is taken for use, the said supervisory relay then disconnecting a portion of the ringing circuit from the said talking circuit and establishing the continuity of the talking circuit, and also rendering the said supervisory signal inoperative, the said locking relay then rendering the said source of ringing current and the said interrupter inoperative, provided they are not operated through other similar connecting circuits, said locking relay keeping itself in operated position until connection is disestablished with the line, and said supervisory relay becoming deenergized upon the discontinuance of the use of the line with which connection is made, whereby the supervisory signal is operated.
9. In a telephone system having lines, a connecting circuit for the lines, said connecting circuit having a talking strand therethrough, a source of calling current normally connected directly with at least a portion of said talking strand, means apart from the circuit of the said source of calling current, for producing periodic ringing over said talking strand and a line when connection is made therewith, and a locking relay opening the circuit of the said source of calling current when the line is taken for use while connection is made therewith, said locking relay then closing a circuit of its own whereby it is held in operated position until connection is disestablished with the line.
10. In a telephone system having lines, a connecting circuit for the lines, said connecting circuit having a talking strand therethrough, said talking strand being normally divided into sections, a source of calling current normally connected with a section of said talking strand, a relay for applying calling current to a line when connection is made therewith, means for producing periodic ringing over said talking strand and the line when connection is made therewith, and a locking relay opening the circuit of the said source of calling current when the line is taken for use while connection is made therewith, said locking relay then closing a circuit of its own whereby it is held in operated position until connection is disestablished with the line.
11. In a telephone system having lines, the combination of a connecting circuit for the lines, said connecting circuit terminating in a pair of connecting plugs, an operator's telephone set normally disconnected from the connecting circuit, said telephone set having a transmitter the battery circuit of which is normally open, and a differential relay controlling the connection of the operator's set with the connecting circuit and the battery circuit through the operator's transmitter, said relay having a pair of windings connected with the respective connecting plugs, whereby the connection of either one of the said connecting plugs with a line connects the operator's telephone set with the connecting circuit for conversational purposes, and whereby the connection of both of the said connecting plugs with the lines causes the operator's telephone set to be disconnected from the connecting circuit and the operator's transmitter battery circuit to be opened.
12. A telephone exchange system including telephone lines extending to an exchange, connecting apparatus for uniting lines in conversation, operator's telephonic apparatus including a telephonic transmitter, a source of current for supplying said transmitter with operating current, and mechanism governed by the connecting apparatus for controlling the application of current by way of the connecting apparatus to the operator's transmitter.
13. A telephone exchange system including telephone lines extending to an exchange, connecting apparatus for uniting lines in conversation, operator's telephonic apparatus including a telephonic transmitter, a source of current for supplying said transmitter with operating current, and electro-magnetic mechanism governed by the connecting apparatus for controlling the application of current by way of the connecting apparatus to the operator's transmitter.
14. A telephone exchange system including telephone lines extending to an exchange, connecting apparatus for uniting lines in conversation, operator's telephone apparatus, and electro-magnetic mechanism for automatically controlling the association of said apparatus with said connecting apparatus and for controlling the application of current to the operator's transmitter by way of the connecting apparatus.
15. A telephone exchange system including telephone lines extending to an exchange,

- connecting apparatus for uniting lines in conversation, operator's telephone apparatus including a telephone transmitter, a source of current for supplying said transmitter 5 with operating current, and mechanism governed by the connecting apparatus for controlling the application of current to the operator's transmitter by way of the connecting apparatus.
- 10 16. A telephone exchange system having a common battery and including telephone lines extending to an exchange, connecting apparatus for uniting lines in conversation, operator's telephone apparatus including a telephone transmitter in circuit connection with the common battery, a source of current for supplying said transmitter with operating current, and electro-magnetic mechanism governed by the connecting apparatus 15 for controlling the application of current to the operator's transmitter.
17. A telephone exchange system including telephone lines extending to an exchange, operator's telephone apparatus, and electro-magnetic mechanism whose operation is effected when said connecting apparatus is united with a calling line for the purpose of associating the operator's telephone outfit with the calling line and supplying the operator's transmitter with operating current, and which electro-magnetic mechanism is released when the connecting apparatus is united with a called line, thereby to exclude the operator's telephone set from circuit.
- 30 18. A telephone exchange system including telephone lines extending to an exchange, operator's telephone apparatus, and electro-magnetic mechanism for including the operator's telephone set in circuit and supplying the transmitter thereof with operating current, said mechanism including an electro-magnet having differentially wound coils, the circuit through one of which being controlled by the connecting apparatus and apparatus associated with the calling line and the circuit through the other of which being controlled by the connecting apparatus and apparatus associated with the called line.
- 45 19. A telephone exchange system including telephone lines extending to an exchange, operator's telephone apparatus, and electro-magnetic mechanism for including the operator's telephone set in circuit and supplying the transmitter thereof with operating current, said mechanism including an electro-magnet having differentially wound coils, the answering end of the connecting apparatus entering into the control of one coil and the connecting end of the connecting apparatus entering into the control of the other coil.
- 60 20. A telephone exchange system including telephone lines extending to an exchange, operator's telephone apparatus, and electro-
- magnetic mechanism for supplying the operator's transmitter with operating current, said mechanism including an electro-magnet having differentially wound coils, the circuit through one of which being controlled by the connecting apparatus and apparatus associated with the calling line and the circuit through the other of which being controlled by the connecting apparatus and apparatus associated with the called line.
- 70 21. A telephone exchange system including telephone lines extending to an exchange, operator's telephone apparatus, and electro-magnetic mechanism for supplying the transmitter thereof with operating current, said mechanism including an electro-magnet having differentially wound coils, the answering end of the connecting apparatus entering into the control of one coil and the connecting end of the connecting apparatus entering into the control of the other coil.
- 75 22. A telephone system including telephone lines extending to an exchange from sub-stations, jack switches in association with the telephone lines, connecting plugs for engagement with said switches, a source of signaling current for operating the signal receivers at called sub-stations, a relay permitting the separation of each connecting plug from the source of signaling current, switching mechanism governed by the associate connecting plug for operating said relay to connect the plug with the source of ringing current, and thereby to transmit the ringing current to the called station, a second relay serving, when inert, to permit of the connection of the signaling current with the connecting plug by the switching mechanism controlled by the first aforesaid relay and adapted to have circuit closed there- 100 through by the switching mechanism at the called sub-station when the signal is responded to thereat, and thereby to remove the signaling current from the called line, a third relay having switching mechanism serving, when unattracted, to dissociate the signaling current from the calling line and to permit of the passage of such current to the called line, and an interrupter included in circuit with said last relay, whereby signaling current is intermittently applied to the called line, the second relay, when energized, opening said interrupter circuit.
- 105 23. A telephone system including telephone lines extending to an exchange from sub-stations, jack switches in association with the telephone lines, connecting plugs for engagement with said switches, a source of signaling current for operating the signal receivers at called sub-stations, a relay permitting the separation of each connecting plug from the source of signaling current, switching mechanism governed by the associate connecting plug for operating said relay to connect the plug with the source of 110 115 120 125 130

ringing current, and thereby to transmit the ringing current to the called station, a second relay serving, when inert, to permit of the connection of the signaling current with the connecting plug by the switching mechanism controlled by the first aforesaid relay and adapted to have circuit closed therethrough by the switching mechanism at the called sub-station when the signal is responded to thereat, and thereby to remove the signaling current from the called line, a third relay having switching mechanism serving, when unattracted, to dissociate the signaling current from the calling line and to permit of the passage of such current to the called line, an interrupter included in circuit with said last relay, whereby signaling current is intermittently applied to the called line, the second relay, when energized, opening said interrupter circuit, and a locking circuit for the second relay established when it is energized and breakable at the exchange.

24. A telephone system including telephone lines extending to an exchange from sub-stations, jack switches in association with the telephone lines, connecting plugs for engagement with said switches, a source of signaling current for operating the signal receivers at called sub-stations, a relay serving, when inert, to permit of the connection of the signaling current with the connecting plug and adapted to have circuit closed therethrough by the switching mechanism at the called sub-station when the signal is responded to thereat, and thereby to remove the signaling current from the called line, a second relay having switching mechanism serving, when unattracted, to dissociate the signaling current from the calling line to permit of the passage of such current to the called line, and an interrupter included in circuit with said second relay, whereby signaling current is intermittently applied to the called line, the first relay, when energized, opening said interrupter circuit.

25. A telephone system including telephone lines extending to an exchange from sub-stations, jack switches in association with the telephone lines, connecting plugs for engagement with said switches, a source of signaling current for operating the signal receivers at called sub-stations, a relay serving, when inert, to permit of the connection of the signaling current with the connecting plug and adapted to have circuit closed therethrough by the switching mechanism at the called sub-station when the signal is responded to thereat, and thereby to remove the signaling current from the called line, a second relay having switching mechanism serving, when unattracted, to dissociate the signaling current from the calling line and to permit of the passage of such current to the called line, an interrupter included in cir-

cuit with said second relay, whereby signaling current is intermittently applied to the called line, the first relay, when energized, opening said interrupter circuit, and a locking circuit for the said relay established when it is energized and breakable at the exchange.

26. A telephone exchange system including telephone lines extending from sub-stations to an exchange, a cord circuit uniting lines in conversation, a ringing current generator, an electro-magnet for each cord circuit serving, when inert, to include the source of ringing current in circuit relation with the signal bell at the called station and having two circuits, one establishable at the called station when the party there responds and the other establishable by said electro-magnet, said electro-magnet, when energized, serving to remove the calling generator from circuit relation with the called line.

27. A telephone exchange system including telephone lines extending from sub-stations to an exchange, a cord circuit for uniting lines in conversation, a ringing current generator, an electro-magnet for each cord circuit serving, when inert, to include the source of ringing current in circuit relation with the signal bell at the called station and having two circuits, one establishable at the called station when the party there responds, and the other establishable by said electro-magnet, said electro-magnet, when energized, serving to remove the calling generator from circuit relation with the called line, the circuits for said electro-magnet including switching mechanism governed by an associate connecting plug.

28. A telephone exchange system including telephone lines extending from sub-stations to an exchange, a cord circuit for uniting lines in conversation, a ringing current generator, an electro-magnet for each cord circuit serving, when inert, to include the source of ringing current in circuit relation with the signal bell at the called station and having two circuits, one establishable at the called station when the party there responds, and the other establishable by said electro-magnet, said electro-magnet, when energized, serving to remove the calling generator from circuit relation with the called line, the circuit that is establishable by the electro-magnet being governed by the connecting plug, so that it may be opened when the parties are through, again to make said electro-magnet inert to enable the generator controlled thereby again to be included in circuit relation with a called line.

29. A telephone exchange system including telephone lines extending from sub-stations to an exchange, a cord circuit for uniting lines in conversation, a ringing current generator, an electro-magnet for each cord

- circuit serving, when inert, to include the source of ringing current in circuit relation with the signal bell at the called station and having two circuits, one establishable at the 5 called station when the party there responds, and the other establishable by said electro-magnet, said electro-magnet, when energized, serving to remove the calling generator from circuit relation with the called line, 10 the circuits for said electro-magnet including switching mechanism governed by an associate connecting plug, the circuit that is establishable by the electro-magnet being governed by the connecting plug, so that it 15 may be opened when the parties are through again to make said electro-magnet inert to enable the generator controlled thereby again to be included in circuit relation with a called line.
- 20 30. A telephone exchange system including telephone lines extending from sub-stations to an exchange, a link connector uniting lines in conversation, a ringing current generator, an electro-magnet for each link 25 connector serving, when inert, to include the source of ringing current in circuit relation with the signal bell at the called station and having two circuits, one establishable at the called station when the party there responds 30 and the other establishable by said electro-magnet, said electro-magnet, when energized, serving to remove the calling generator from circuit relation with the called line.
- 35 31. A telephone exchange system including telephone lines extending from sub-stations to an exchange, a link connector for uniting lines in conversation, a ringing current generator, an electro-magnet for each 40 link connector serving, when inert, to include the source of ringing current in circuit relation with the signal bell at the called station and having two circuits, one establishable at the called station when the party 45 there responds, and the other establishable by said electro-magnet, said electro-magnet, when energized, serving to remove the calling generator from circuit relation with the called line, the circuits for said electro-magnet 50 net including switching mechanism governed by an associate connecting terminal.
32. A telephone exchange system including telephone lines extending from sub-stations to an exchange, a link connector for 55 uniting lines in conversation, a ringing current generator, an electro-magnet for each link connector serving, when inert, to include the source of ringing current in cir-

cuit relation with the signal bell at the called station and having two circuits, one 60 establishable at the called station when the party there responds, and the other establishable by said electro-magnet, said electro-magnet, when energized, serving to remove the calling generator from circuit relation 65 with the called line, the circuit that is establishable by the electro-magnet being governed by the connecting terminal, so that it may be opened when the parties are through, again to make said electro-magnet inert to 70 enable the generator controlled thereby again to be included in circuit relation with a called line.

33. A telephone exchange system including telephone lines extending from sub-stations to an exchange, a link connector for uniting lines in conversation, a ringing current generator, an electro-magnet for each link connector serving, when inert, to include the source of ringing current in circuit relation with the signal bell at the called station and having two circuits, one establishable at the called station when the party there responds, and the other establishable by said electro-magnet, said electro-magnet, when 80 energized, serving to remove the calling generator from circuit relation with the called line, the circuits for said electro-magnet including switching mechanism governed by an associate connecting terminal, the circuit 85 that is establishable by the electro-magnet being governed by the connecting terminal, so that it may be opened when the parties are through again to make said electro-magnet inert to enable the generator controlled thereby again to be included in circuit 90 relation with a called line.

34. A telephone exchange system including telephone lines extending from sub-stations to an exchange, link circuits for uniting lines in conversation, a source of signaling current, a switch normally connecting said source of signaling current with the link circuits, and mechanism for operating said switch to remove the generator from 100 circuit and itself operated by apparatus at the called substation.

As inventors of the foregoing we hereunto subscribe our names in the presence of two subscribing witnesses, this 14th day of September, 1908.

ELMER R. CORWIN.
CHARLES A. BALS.

Witnesses:

FREDERICK R. PARKER,
H. Roy Cook.
